(57) **CLAIM**

The ornamental design for a beverage container cap, as shown and described.

DESCRIPTION

FIG. 1 is a top isometric view of a beverage container cap showing the design.

FIG. 2 is a bottom isometric view thereof;

FIG. 3 is a first side elevation view thereof;

FIG. 4 is a second side elevation view thereof;

FIG. 5 is a third side elevation view thereof;

FIG. 6 is a fourth side elevation view thereof;

FIG. 7 is a top plan view thereof;

FIG. 8 is a bottom plan view thereof; and

FIG. 9 is a detail view of the portion of the design bounded by a dash-dot line in FIG. 3.

FIG. 10 is a top isometric view of a beverage container cap showing a second embodiment of the design;

FIG. 11 is a bottom isometric view thereof;

FIG. 12 is a first side elevation view thereof;

FIG. 13 is a second side elevation view thereof;

FIG. 14 is a third side elevation view thereof;

FIG. 15 is a fourth side elevation view thereof;

FIG. 16 is a top plan view thereof; and,

FIG. 17 is a bottom plan view thereof.

The shading lines shown in the drawings represent the three-dimensional contour of the claimed design and are not intended to indicate surface decoration. The dashed lines shown in the drawings illustrate portions of the beverage container cap that form no part of the claimed design.
